JETTY

George W. Rehfeld, Manhattan, Kans.

Application September 4, 1943, Serial No. 501,243

5 Claims. (Cl. 61—3)

This invention relates to jetties particularly adapted for use along the banks of streams and upon overflow lands to prevent erosion and effect deposit of silt. Jetties are usually made of structural members arranged to provide a plurality of outwardly extending arms or legs which are interconnected with a wire lacing to provide the desired current retarding surfaces. The practice heretofore has been to construct the arm members of the jetties of heavy rigid material so that they are self-supporting independently of the lacing. This is for the reason that the lacing cannot be depended upon to enhance the strength of the jetties, since the lacing slips out of place along the length of the members under the severe buffeting to which the jetties are subjected.

The extreme rigidity of such jetties prevents their use in navigable streams for the reason that the rigid arm members are apt to puncture the hulls of vessels that might float into contact with them. Also such jetties must contain a substantial amount of material, are heavy, expensive and difficult to install.

Attempts have been made to eliminate weight of the members by forming them of structural shapes; for example, angle irons, and to positively anchor the lacing by threading the lacing through punched or drilled openings, or by providing hooks sheared from the flanges of the angle members, but this has not proved satisfactory because of added manufacturing cost and the structural members have been weakened by reduction in cross sectional area at the points of anchoring the lacing.

Machining of the metal also exposes surfaces which are more readily subject to rust and corrosion and provide sharp edges that cut through the lacing. When the lacing is severed the angle members are apt to double over under force of the current, usually at one of the anchoring openings or at the point where the members are interconnected so that they no longer serve their intended purpose.

It is the purpose of the present invention to overcome these difficulties by providing relatively lightweight jetty arms having a substantial degree of flexibility so that under stress they are capable of bending uniformly throughout their length, and by providing lacing anchors along the length of the jetty arms that project from the surfaces thereof for preventing shifting of the lacing without reducing the cross sectional area of the members.

Flexibility of the jetty arms also allows for use of the jetties in navigable streams as they are

readily deflected when struck by the hull of a vessel and the force of the blow is absorbed in flexing of the arms rather than causing them to pierce the shell of the vessel.

Other objects of the invention are to provide a jetty having metal arms inherently covered with a rust resistant coating; to provide for elimination of machining operations that ordinarily expose surfaces to corrosion; to provide for welding the members together in forming a unitary structure; to provide positive anchorage for the lacing so that the lacing cooperates to support the arms of the jetty; and to provide an anchorage for the lacing that retains its positive connection under flexure of the arms.

In accomplishing these and other objects of the invention hereinafter pointed out, I have provided improved structure, the preferred form of which is illustrated in the accompanying drawing, wherein:

Fig. 1 is a perspective view of a jetty constructed in accordance with the present invention.

Fig. 2 is a fragmentary perspective view illustrating anchorage of the lacing rods prior to bending over the anchoring fingers.

Fig. 3 is a similar view after the fingers have been bent to retain the lacing rod.

Fig. 4 is a fragmentary perspective view of the central portion of the jetty particularly illustrating connection of the arm and leg members of the jetty.

Fig. 5 is a fragmentary perspective view of the outer end of one of the arms.

Fig. 6 is a fragmentary perspective view of a portion of a jetty arm equipped with a modified form of lacing anchor lug.

Referring more in detail to the drawing:

1 designates a jetty constructed in accordance with the present invention and which includes a plurality of elongated rod or bar-like members 2 arranged in crossing relation with the ends thereof extending outwardly in opposite directions to provide the desired spread of lacing 3, later described.

In carrying out the present invention, the members 2 comprise metal bars or rods having substantially uniform cross section throughout the length thereof and capable of yielding uniformly when subjected to buffeting action of heavy driftage. The surfaces of the members are also provided with a rust resistant coating so that the members have a substantially long life when subjected to salt water, or waters containing corrosive materials.

I have found that rods or bars such as used

in the reinforcement of concrete structures have all the above qualifications and are readily obtainable for use in jetty construction. Reinforcing bars provide the desired flexibility, have the necessary toughness and strength, and flex uniformly throughout their length. Reinforcing bars also have a natural coating or scale covering the surfaces thereof so that they are protected from rust and corrosion. The metal of reinforcing bars also provide for ready welding of the bars at the site of installation, preferably by electric arc welding, so that assembled they form a sturdy unit, free of racking, when the arms are under stress. Reinforcing bars also have rounded edges so that they do not cut the lacing members and, being of solid cross section, they provide maximum strength for a given amount of metal. Furthermore, reinforcing bars may be obtained which are provided with uniformly spaced deformations 4 projecting laterally from the surfaces thereof which provide positive stops to prevent shifting of the lacing on the bars.

In cooperation with the deformations 4, I may provide the bars with lacing anchors 5 which are shown in Fig. 2 as comprising substantially U-shaped clips having bar portions 6 and projecting fingers or lugs 7 and 8 spaced apart to accommodate the lacing therebetween. The anchors 5 are formed of formable material and are attached to the bars at spaced intervals along the length thereof by welding the bar portions 6 to corners of the bars, as indicated at 9 so that the fingers 7 and 8 extend laterally from the bars as shown in Fig. 2. The anchors may be welded to the corner edges of the bars as illustrated in Fig. 2, or they may be welded to the face sides that carry the deformations 4. I find that positions on or adjacent the corner edges of the bars are most convenient for welding and for ready application of the lacing 3.

In Fig. 6 I have illustrated a modified form of lacing anchor which comprises a short length rod or wire 12 welded transversely of the jetty bars, as indicated at 13 to provide laterally extending fingers about which the lacing may be wrapped.

The outer-most anchors are preferably welded as at 16 to the end faces 17 of the bars so that the fingers thereof normally extend in the direction of the arms to permit ready seating of the outer-most lacing 3.

In assembling the jetty, reinforcing rods or bars having a dimension to provide the necessary strength are cut to the desired length and the anchors 5 are welded therewith for receiving the inner lacing of the jetty. Anchors 5 are also welded to the end faces 17 of the bars, after which the bars are arranged in crossed relation.

The jetty illustrated is composed of three bars, 18, 19 and 20. The bars 18 and 19 are crossed intermediate their ends and the corner edges 21 and 22 are welded transversely of the face 23 of bar 18 as indicated at 24, Fig. 4, and the edges 25 and 26 of the bar 18 are welded to the face 27 of the bar 19, as indicated at 28. The bar 20 is then placed within one of the angles formed between the bars 18 and 19 with adjacent faces 28 and 29 thereof contacting faces 30 and 31 of the bars 18 and 19. The corner edges 32 and 33 of the bar 20 are then welded to the face 31 of the bar 19, as indicated at 34, and the corner edges 35 and 36 of the bar 18 are welded to the face 29 of the bar 20, as indicated at 37. When thus welded the bars are retained in rigid assembly at the joint and the contacting faces

thereof are sealed against entrance of corrosive fluids which may ordinarily tend to produce electrolysis between the respective members of the jetty. While I prefer to weld the bars in assembly, it is possible to provide other fastening means, such as clamps or the like, which do not result in weakening of the bars.

While the bars are rigidly secured at their crossing points, the ends thereof are free to flex 10 within the limits of the lacing and any stresses acting on the bars produces a bend therein substantially uniform throughout the length of the arms so that the strains are not localized at any one point as in the case of structural members having flanges or members drilled and/or sheared to receive the lacing.

After assembly of the bar members of the jetty, the lacing 3 is applied in any suitable arrangement. While the lacing 3 may comprise wire or cable, I prefer to use a continuous length rod, as I find rods provide greater strength and have a natural rust resistant surface. The rod lacing is also readily formable about the bar members of the jetty. The rod lacing is passed between the fingers 7 and 8 of the anchors and is preferably wrapped at least one turn about the body of the arms as shown in Fig. 2. The portions of the rod lacing that extend about the bar contact the deformations 4 so that the deformations cooperate with the fingers 7 and 8 of the anchors to prevent shifting of the lacing on the arms of the jetty. After the lacing has been applied the fingers 7 and 8 are bent over as shown in Fig. 3 to close the space therebetween and securely retain the lacing therein. The fingers of the end-most anchors are likewise bent as shown in Fig. 3 to complete the jetty assembly. A jetty thus assembled is of relatively light weight, is relatively inexpensive, has substantial strength, and is capable of withstanding the buffeting effects to which jetties are subjected.

A jetty constructed of material above described is more resistant to corrosion, the lacing is better supported on the arms, and even when they are bent out of position, the arms still perform their intended function.

Attention is also directed to the fact that the deformations 4 provide additional surfaces and projections for catching debris which facilitates retard of the current and hastens the deposit of silt through greater retardation of the current.

While I have specifically illustrated and described bars or rods of substantially square cross section, it is to be understood the invention pertains to any shape of reinforcing bars of rod-like character.

I have particularly illustrated and described the lacing as attached by the anchors 5 or 12, or the lacing may be attached by welding to the bars, or the deformations 4 may provide, in many instances, an adequate and positive anchorage for the lacing. However, if ordinarily smooth rods are employed in forming the members of the jetty, the anchors 5, or their equivalent, are essential in providing a positive anchorage of the lacing.

What I claim and desire to secure by Letters Patent is:

1. A jetty including a plurality of flexible rod-like members having solid and substantially uniform cross section throughout the length thereof, means connecting the members together to provide a plurality of radially extending yieldable arm and leg portions, lacing connecting said arm and leg portions, and lugs projecting from the

surfaces of said members to provide anchorage for the lacing, said lugs being provided without reducing the metal contained within the cross section of said members at the points of the lugs.

2. A jetty including a plurality of rod-like members having solid and substantially uniform cross section throughout the length thereof, means connecting the members together to provide a plurality of radially extending arm and leg portions, lacing connecting said arm and leg portions, lugs projecting from the surfaces of said members to provide anchorage for the lacing, said lugs being formed without reducing the metal contained within the cross section of said members, and clips having welded connection with said members and provided with portions adapted to be bent over the lacing at said points of anchorage to positively anchor said lacing.

3. A jetty including a plurality of flexible rod-like members, each comprising a reinforcing bar having spaced deformations projecting from surfaces of the bar, means connecting the members together in crossed relation to provide a plurality of radially extending flexible arm and leg

portions, and lacing connecting said arm and leg portions at points intermediate said deformations.

4. A jetty including a plurality of rod-like members arranged in crossed relation, each comprising a reinforcing bar having projecting deformations a plurality of fingers projecting from surfaces of said members, lacing connecting said members and engaging said fingers, said fingers being bendable across the lacing for positively anchoring the lacing relatively to the rod-like members.

5. A jetty including a plurality of rod-like members arranged in crossing relation forming radially, extending substantially flexible arm and leg portions, U-shaped clips having bar portions welded to said members and having laterally projecting fingers forming lacing-engaging portions therebetween, and lacing wrapped about said members and passing through said lacing-engaging portions of the clips, said fingers being bendable over said lacing to positively anchor the lacing on said members.
